(57) **CLAIM**

The ornamental design for a convertible garment, substantially as shown and described.

DESCRIPTION

FIG. 1 is a front isometric view of a convertible garment showing my design.

FIG. 2 is a front view of FIG. 1.

FIG. 3 is a rear view of FIG. 1.

FIG. 4 is a right side view of FIG. 1.

FIG. 5 is a left side view of FIG. 1.

FIG. 6 is a top view of FIG. 1.

FIG. 7 is a bottom view of FIG. 1.

FIG. 8 is a front isometric view of the convertible garment of FIG. 1 with the sleeves removed from the jacket and worn as a vest and leggings.

FIG. 9 is a front view of FIG. 8.

FIG. 10 is a rear view of FIG. 8.

FIG. 11 is a right side view of FIG. 8.

FIG. 12 is a left side view of FIG. 8.

FIG. 13 is a top view of FIG. 8; and,

FIG. 14 is a bottom view of FIG. 8.

The broken line showing of the humanoid figure, shirt, shorts, and shoes in FIGS. 1 and 8-14 form no part of the claimed design. The broken lines in the drawings showing portions of the convertible garment form no part of the claimed design.

1 Claim, 10 Drawing Sheets
